UNITED STATES PATENT OFFICE.

ERNEST ZEIDLER, OF MARSHFIELD, WISCONSIN.

BOX.

1,391,038.

Specification of Letters Patent. Patented Sept. 20, 1921.

Application filed February 7, 1921. Serial No. 443,024.

To all whom it may concern:

Be it known that ERNEST ZEIDLER, a citizen of the United States, residing at Marshfield, in the county of Wood and State of Wisconsin, has invented certain new and useful Improvements in Boxes, of which the following is a specification, reference being had therein to the accompanying drawing.

The invention relates to boxes and particularly to cylindrical cheese boxes, and has for its object to provide a box of this character wherein the lower edges of the body portion of the box are held together by the strip of metal right angular shaped in cross section, the flanges of metallic strip being secured to the side and the bottom of the box, and to provide a substantially similarly shaped and connected strip carried by the box top and provided with an annular rib adjacent its angling point, said annular rib being of substantially the same diameter as the diameter of the metallic strip carried by the body of the box, and adapted to receive the lower end of the body of the box when boxes are super-imposed. By this particular construction the main object of the invention is obtained, that is, the prevention of sliding of the boxes when they are super-imposed in shipment. Also to so proportion the metallic strip carried by the bottom and the rib that starting of sliding will be prevented, and the flange carried by the bottom metallic strip will rest upon the flange carried by the metallic strip of the top of the box, thereby maintaining the boxes, that is the destructible part of the boxes out of contact when superimposed.

A further object is to provide the flanges of the metallic strips, which engage the bottom of the body portion of the box and the top of the cover of the box with crimping, which interengage when the boxes are superimposed, thereby preventing circumferential movement of the boxes in relation to each other when stacked.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

55 In the drawings:

Figure 1 is a top plan view of the box.

Fig. 2 is a sectional view through the box taken on line 2—2 showing the same superimposed on another box.

Fig. 3 is a detail perspective view of a portion of the metallic angle member carried by the cover of the box.

Referring to the drawing, the numeral 1 designates the body of the box, and 2 the removable cover carried thereby. The box as a whole is a cylindrical one and of the type used for storing and shipping cheese. It has been found during shipment that when the boxes were superimposed in freight cars, that the boxes which are now in use slide, incident to jolting of the train and as the contents of the box is heavy, the boxes become damaged and in many cases where they slide off of the stacks are entirely destroyed and the contents damaged. To obviate this difficulty the top 2 of the box is preferably formed of wood and the flange 3 formed of fiber board, the upper edge of which is disposed in an annular channel 4, said flange 3 being held in the channel 4 by means of an angularly shaped band 5 which extends around the top, said band having its vertical flange 6 stapled or otherwise secured to the cover flange 3, and its flange 7 stapled or otherwise secured to the upper side of the wooden cover. Adjacent the point of the band 5, an annular rib 8 is formed; however the flange 7 is crimped as at 9, the purpose of which will presently appear.

The lower edge of the body 1 of the box is provided with an annular metallic strip 10 substantially right angle in cross section and has its flange 11 secured as at 12 to the side of the body of the box and its flange 13 secured as at 14 to the wooden member 15 forming the bottom of the box, thereby securing the bottom 15 in the body 1 of the box, and at the same time reinforcing the lower edge of the body. Flange 13 is crimped as at 16, thereby allowing the metallic strips to be formed from straight material, and at the same time providing a serrated surface for engaging the serrated surface of the flange 7 of the cover 2 when boxes are superimposed or stacked for storage or shipment. By providing these serrated surfaces, it will be seen that they will interengage in such a manner that circumferential movement of the stacked boxes in relation to each other, will be prevented and the tendency to slide incident to shipment while in a stacked condition obviated to a

certain extent. However to insure the boxes against sliding when stacked, the strip 10 is so proportioned in diameter in relation to the diameter of the rib 8 that it will be received within said rib and will substantially engage said rib in such a manner that they will be prevented from starting to slide or gaining momentum sufficient to cause them to slide over the ribs 8. The metallic strips 10 and 5 may be formed in any suitable manner, however they are preferably formed from strips of material in angular form, then one of the flanges crimped thereby causing the strip to be formed into a ring and the ends of said ring may be secured together in any suitable manner, however they are preferably secured together by spot welding.

From the above it will be seen that a box 20 is provided having its bottom and its cover so proportioned that when they are superimposed the bottoms of the boxes will be received within a bead carried by the cover in such a manner that the boxes will not slide 25 in relation to each other while in transit, and also that the bead is formed as an integral part of an angularly shaped reinforcing band reinforcing and connecting together the top and the flange of the top. It will 30 also be seen that the boxes are so constructed and proportioned that when they are superimposed only metallic parts will be in engagement.

The invention having been set forth what 35 is claimed as new and useful is:—

1. The combination with a cylindrical box comprising a body portion and a cover, said cover having its flange secured thereto by

means of a metallic band substantially right angularly shaped and having one of its flanges secured to the upper surface of the cover and the other flange secured to the cover flange, of an annular bead formed at the angling point of the metallic band and extending upwardly, said annular bead being 45 of substantially the same interior diameter as the diameter of the bottom of the box, and adapted to receive the bottom of a superimposed box and hold the same against lateral displacement while in transit. 50

2. The combination with a cylindrical box comprising a body portion and a cover, the upper edge of the cover and the bottom edge of the body portion being provided with metallic bands right angularly shaped in 55 cross section and forming means for holding the cover together and the body portion together, one flange of the band carried by the body portion engaging the bottom of the body and provided with a plurality of 60 crimps extending entirely around the flange, one flange of the band carried by the cover engaging the upper side of the cover and provided with a plurality of crimps, a bead 65 annular in shape extending upwardly from the band carried by the cover, said bead being of substantially the same interior diameter as the diameter of the band carried by the bottom of the body of the box and adapted to receive the bottom of an 70 adjacent box, said crimped flange being so disposed that when the boxes are superimposed they will engage each other.

In testimony whereof I hereunto affix my signature.

ERNEST ZEIDLER.
